(57) **CLAIM**

The ornamental design for a snow rake, as shown and described.

DESCRIPTION

FIG. 1 is a front, right side, top perspective view of a snow rake showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The snow rake is shown with symbolic breaks in its length. The appearance of any portions of the article between the break lines forms no part of the claimed design.
